FASTENER FOR CONTAINER COVERS

Walter E. Heller, St. Paul, Minn., assignor to
David C. Shepard, St. Paul, Minn.Application March 13, 1933, Serial No. 660,447
Renewed February 6, 1935

19 Claims. (Cl. 217—89)

My invention relates to fasteners for container covers and particularly to covers used in conjunction with containers open at their upper ends.

An object of the invention resides in providing

5 a fastener whereby such cover may be either temporarily or permanently secured to the container with which it is used.

An object of the invention resides in providing a fastener for container covers by means of which 10 the cover may be readily and easily applied to or removed from the container.

Another object of the invention resides in constructing the container with a downwardly facing shoulder and in providing the cover with a member having a part for engagement with said shoulder to hold the cover attached to the container.

15 An object of the invention resides in providing a resilient member for engagement with the shoulder of said container.

A still further object of the invention resides in constructing the open end of the container with a hoop encircling the same and forming the downwardly extending shoulder.

20 A feature of the invention resides in providing a plurality of fasteners secured to said cover for engagement with said shoulder at various localities about the periphery thereof.

An object of the invention resides in providing 25 a retaining member for holding said fastener members into engagement with said shoulder.

A feature of the invention resides in constructing 30 said fastener members with bights and in providing an elongated retainer member embracing all of said fastener members and lodged within the bights thereof.

An object of the invention resides in constructing 35 said members with fingers adapted to engage beneath the shoulder of the container, said bights being formed in proximity to said fingers.

A still further object of the invention resides in constructing the cover with a body portion and a flange depending therefrom and in providing the fastener members with parts imbedded within the body of the cover and with other parts imbedded in the flange thereof and issuing outwardly from the lower edge of the flange of the cover.

An object of the invention resides in constructing 45 said fastener members with eyes having parts adapted to extend beneath the shoulder of the container and forming abutments for engagement therewith and in threading said retaining member through the eyes of said fastener members.

50 A still further object of the invention resides

in constructing said fingers with cam surfaces for moving said fingers into a position to permit of the application of the cover to the container.

Other objects of the invention reside in the 5 novel combination and arrangement of parts and in the details of construction hereinafter illustrated and/or described.

In the drawing:

Fig. 1 is a perspective view of a container illustrating the application of my invention thereto.

Fig. 2 is a fragmentary sectional view taken on line 2—2 of Fig. 1.

Fig. 3 is a perspective view of one of the fasteners used with the invention.

Fig. 4 is a perspective view of the cover shown in Fig. 1 detached from the container proper and illustrating a modified form of fastener applied thereto.

Fig. 5 is a view similar to Fig. 2 showing a 10 modification of the invention.

Fig. 6 is a view similar to Figs. 2 and 5 showing still another form of the invention.

For the purpose of illustrating the application of my invention, I have shown a container 10 which is constructed with a wall structure 11 best illustrated in Fig. 2. The container is open at the top as indicated at 12 and is closed at the lower end thereof through a bottom, not shown. Inasmuch as the particular construction of the 15 container forms no feature of the invention, the same has not been described in detail in this application, though it can readily be comprehended that any suitable construction such as is now well known in the art may be employed.

The open end 12 of the container 10 is closed through a cover 13 (Figs. 2 and 3). This cover is constructed with a body portion 14 which covers the open end 12 of the container and is further constructed with a flange 15 which extends downwardly from the body portion and along the wall 11 of the container.

A hoop 16 encircles the upper end of the wall structure 11 of the container proper and is rigidly secured thereto. Where the container is constructed of paper, hoop 16 may be likewise constructed of paper and glued to the wall structure 11. Where other forms of construction are employed, the hoop may be constructed in the customary manner and secured to the wall structure 45 in any suitable manner. The hoop 16 is formed with a downwardly facing shoulder 17 by means of which the cover 13 is held attached to the container proper.

Distributed about the periphery of the cover 50

13 are a number of fastener members 18, 19, 20, and 21. All of these fastener members being identical in construction, only the fastener member 21 will be described in detail. This fastener member is shown in detail in Fig. 4 and is constructed from a length of resilient flat ribbon or a metal strip which is formed in the desired shape by bending. This fastener member consists of a part 22 which is adapted to be imbedded in the 10 flange 15 of the said cover. Another part 24 depends from the part 23 and is formed at its extreme end with a looped portion 25 which forms an eye 26 and an abutment 27 at the upper end thereof. When the cover is applied, part 24 follows along the lower portion of the hoop 16 which is considerably longer than the flange 15 and the abutment 27 extends beneath the shoulder 17 engaging the same and holding the cover attached to the container.

15 The cover 13 may, if desired, be constructed from sheets of paper glued together and pressed in suitable dies to form the body portion 14 and flange 15. When the cover is so constructed a number of sheets from which the same is formed 20 are first placed one upon the other with a suitable adhesive therebetween. The fasteners 18, 19, 20, and 21 are next placed upon the sheets so disposed and the remainder of the sheets placed upon these fasteners. Thereafter the 25 composite structure is pressed in suitable dies to form the body portion 14 and flange 15 and the formed cover allowed to set and dry. When properly cured an extremely rigid and substantial cover construction results in which the fasteners are firmly imbedded. When the cover is 30 so constructed the parts 22 of the fasteners become imbedded in the body portion 14 of the cover and the parts 23 in the flange 15.

35 In the application of the cover to the container the following is the procedure. The parts 24 of the various fasteners are normally bent inwardly as best shown in Figs. 2 and 3. In applying the cover to the container the cover is placed upon the open end of the container with the looped portions 25 resting upon the upper edge 28 of the hoop 16. Due to the fact that the portions 25 are 40 circular in form the lower edges 29 thereof are curved and operate as cams which engage the corners of the upper edge 28 of the hoop 16 and causes the parts 24 of the fasteners to spread 45 outwardly and allow the looped portions 25 to follow along the outer surface 30 of the hoop 16. When these portions come below the fastener 17 of hoop 16, the resiliency of the parts 24 of the various fastener members cause the said looped 50 portions to spring beneath the shoulder 17 and to bring the abutments 27 into engagement therewith. The parts are so disposed that when the abutments 27 engage shoulder 17, the under 55 surface 31 of body portion 14 of cover 13 rests upon the upper edge 28 of the hoop 16.

60 After the cover has been applied, as described, the same is temporarily held in place through the action of the abutments 27 and may be removed 65 by the insertion of the fingers beneath the looped portions 25 of some of the fasteners and the bending of the portions 24 of said fasteners outwardly to permit said eyes to clear the hoop 16. The cover 13 may then be raised upwardly at 70 such locality and the procedure completed until sufficient of the fasteners have been disengaged to permit of the removal of the cover from the container.

75 For the purpose of permanently holding the cover 13 applied to the container, a retaining

member 32 is employed which may consist of a piece of wire which is successively threaded through the various eyes 26. The ends of this retaining member are twisted together as indicated at 12. Retaining member 32 becomes lodged beneath the shoulder 17 of hoop 16 intermediate the fastener members 18, 19, 20, and 21 and is firmly seated against the outer surface 34 of the wall structure 11 of the container proper. When the retainer member 32 is so disposed, the 10 same serves to restrain outward movement of the various fastener members and prevents disengagement of the abutment 27 from the shoulders 17 of the hoop 16. In this manner the cover is 15 firmly held attached to the container proper and accidental removal of the same prevented.

If desired, the portions 22 of oppositely disposed fasteners may be formed continuous and may extend completely across the body portion 14 of the cover 13. Such construction is shown in Fig. 4 20 which illustrates two straps 35 and 36 arranged to cross one another and confined within the body 14 of the cover proper. These straps are provided at their ends with downwardly projecting parts 37 similar to the parts 23 and 24 of the 25 form of the invention shown in Fig. 3. At the ends of these parts are provided looped portions 38 identical with the looped portions 25 and which serve the same purpose. In the form of the invention shown in Fig. 2 it becomes impossible 30 to pull the fasteners out of the cover. At the same time the straps 35 and 36 operate to stiffen and reinforce the cover and to prevent breakage thereof when the containers are stacked one upon the other.

In Fig. 5 I have shown another form of the invention which is quite similar to that shown in Fig. 3. In this figure corresponding parts will be indicated by the same reference numerals as in the other form of the invention. The fastener 40 illustrated in Fig. 5 is indicated in its entirety at 39 and is provided at the part 23 thereof with an inwardly extending finger 40 which is adapted to engage beneath the shoulder 17 of the hoop 16. At the end of the finger 40 is provided an angularly disposed part 41 which serves as a cam the same as the part 29 of the looped portion 25 and operates to spread the fasteners apart when the cover is being applied to the container. Between the finger 40 and the part 41 is formed 50 a bight 42. The retainer member 32 instead of being disposed within an eye such as shown in the form of the invention illustrated in Figs. 2 and 3, rests in the bight 42 and is held from movement with respect to the fastener through the 55 same. The manner of using the device shown in Fig. 5 is identical with that shown in Figs. 1 and 2 and the retainer member 32 functions in identically the same manner as previously described.

If desired, the construction shown in Fig. 5 60 may be formed with a looped portion at the end of the part 41. In Fig. 6 such construction is shown in which like reference characters are used to designate similar parts. The looped portion formed at the end of the part 41 in this form 65 of the invention is designated by the reference numeral 43. In this case, the retaining member 32 is threaded through the eye in the looped portion 43 instead of being disposed in the bight 42 as is the case with the form of fastener shown 70 in Fig. 5.

75 My invention is highly advantageous in that an extremely simple and practical construction is provided by means of which the cover for the container may be either permanently or tem-

porarily held attached to the container proper. The cover is easily applied to the container by exerting downward pressure upon the same which through the action on the cams on the fastener members cause the same to become spread apart and to clear the hoop. As soon as the container has arrived at its proper closing position, the abutments or fingers on the fasteners snap into engagement with the shoulder on the hoop there-
5 by holding the cover properly applied to the container. Through the action of the retainer member the fasteners may be permanently held in engagement with the shoulder on the hoop thereby causing the cover to become permanently attached to the container. If desired, the ends of the retainer member may be secured together through a suitable seal for preventing tampering with the contents of the container. When the cover has been properly applied, the parts
10 of the fastener are disposed within the confines of the container as determined by the flange of the cover thereof. My invention can be constructed at an extremely economical cost and from materials readily bent into the desired form and applied to the cover during the construction thereof. Due to the angular parts of the fasteners the fasteners become securely imbedded in the flange and body structure of the cover, thereby preventing the pulling out of the fastener.
15 Where the parts of the fastener are disposed within the body of the cover and extend completely across the same, said parts serve to stiffen and reinforce the cover and at the same time prevent the pulling out of the fasteners.
20

Changes in the specific form of my invention, as herein disclosed, may be made within the scope of what is claimed without departing from the spirit of my invention.

Having described my invention, what I claim as new and desire to protect by Letters Patent is:

1. In combination with a container open at its upper end and a cover therefor having a downwardly extending flange, a downwardly projecting shoulder on said container disposed beneath said flange and a resilient member secured to said flange and having a part projecting below said flange for engagement with said shoulder to hold the cover attached to said container, said part being urged into engagement with said shoulder through the resiliency of said member.

2. In combination with a container open at its upper end and a cover therefor having a downwardly extending flange, a downwardly projecting shoulder on said container disposed beneath said flange and a resilient member issuing outwardly from the lower edge of said flange and having a part adapted to engage said shoulder to hold the cover attached to said container, said part being urged into engagement with said shoulder through the resiliency of said member.

3. In combination with a container open at its upper end and provided with a hoop at its open end having a downwardly facing shoulder, a cover for the open end of said container and a plurality of resilient members attached to said cover, each of said members having a part for engagement with said shoulder, a retaining member embracing all of said resilient members and operating to hold said parts of the resilient members in engagement with said shoulder, and means on said resilient members for holding said retaining member in place with respect to said resilient members.

4. In combination with a container open at its upper end and provided with a hoop at its open

end having a downwardly facing shoulder, a cover for the open end of said container and a plurality of members attached to said cover, each of said members having a part for engagement with said shoulder, a retaining member embracing all of said members and operating to hold said parts of said members in engagement with said shoulder said parts being disposed between said retaining member and said shoulder, and means on said members for holding said retaining member in place with respect to said first named members.

5. In combination with a container open at its upper end and provided with a hoop at its open end having a downwardly facing shoulder, a cover for the open end of said container, having a flange extending downwardly along said hoop, a plurality of members attached to said cover and extending downwardly along said flange and toward said shoulder, fingers formed on said members for engagement with the shoulder of said hoop, and a tie member embracing said fingers for holding the same in engagement with said shoulder, said fingers having means thereon for holding said tie member from movement relative thereto.

6. In combination with a container open at its upper end and a cover therefor having a downwardly extending flange, a downwardly projecting shoulder on said container near the open end thereof and below said flange, an elongated member having a part imbedded within said cover and another part imbedded within said flange and projecting outwardly from the lower edge thereof, and a finger formed on said last named part of said member for engagement with said shoulder.

7. In combination with a container open at its upper end and a cover therefor having a downwardly extending flange, a downwardly projecting shoulder on said container near the open end thereof and below said flange, a resilient member having a part imbedded within said cover and another part imbedded within said flange and projecting outwardly from the lower edge thereof, and a finger formed on said last named part of said member for engagement with said shoulder, said finger being urged into engagement with said shoulder through the resiliency of said member.

8. In combination with a container open at its upper end and provided with a hoop at its open end having a downwardly facing shoulder, a cover for the open end of said container, a plurality of members attached to said cover and extending downwardly along said hoop, said members having fingers thereon for engagement beneath said shoulder, said members having bights formed therein and a retaining member embracing said members for holding said fingers in engagement with said shoulder, said retaining member being lodged within said bights.

9. In combination with a container open at its upper end and provided with a hoop at its open end having a downwardly facing shoulder, a cover for the open end of said container, a plurality of members attached to said cover and extending downwardly along said hoop, said members having eyes on the ends thereof providing abutments for engagement beneath said shoulder and a retaining member threaded through said eyes and encircling said container for holding said abutments against said shoulder.

10. In combination with a container open at its upper end and a cover therefor, a downwardly facing shoulder on said container near the open

end thereof and a plurality of members attached to said cover and overlying said container, said members having shoulders for engagement with the shoulder of said body and means engaging all 5 of said members for holding the shoulders thereof in engagement with the shoulder of said container.

11. In combination with a container open at its upper end and a cover therefor, a downwardly 10 facing shoulder on said container near the open end thereof and a plurality of members attached to said cover and overlying said container, said members having shoulders for engagement with the shoulder of said body and a retaining member 15 encircling all of said members and holding the shoulders thereof into engagement with the shoulder of said container.

12. In combination with a container open at its upper end and a cover therefor, a member on 20 said container formed with a downwardly facing shoulder, a resilient member attached to said cover and overlying said container, said member having a part for engagement with said shoulder, and a cam on said member beyond said part for 25 engagement with the member on said container, said cam operating to flex said resilient member and to guide the engaging part thereof into engagement with the shoulder.

13. In combination with a container open at 30 its upper end and a cover therefor, a member on said container formed with a downwardly facing shoulder, a resilient member attached to said cover and overlying said container, said member having a part for engagement with said shoulder and being movable toward and from the container, said member being normally flexed to urge 35 said engaging part into engagement with said shoulder, and a cam on said resilient member for engagement with the member on the container, said cam causing said flexible member to move 40 in a direction away from the container.

14. In combination with a container open at its upper end and a cover therefor, a downwardly 45 projecting shoulder on said container near the open end thereof and a resilient member attached at its upper end to said cover and depending therefrom, said member having a laterally extending part near its lower end for engagement with the shoulder, all of said resilient 50 member beyond said laterally extending part being disposed below said shoulder.

15. In combination with a container open at its upper end and a cover therefor, a downwardly 55 projecting shoulder on said container near the open end thereof and a resilient member attached to said cover and having a part extending downwardly along said container and another part for engagement with said shoulder, said first named part being bendable to procure movement

of said second named part of said member into and out of engagement with said shoulder, the resiliency of said member operating to urge said second named part into engagement with said shoulder, and a finger piece on said member for disengaging the second named part from said shoulder.

16. In combination with a container open at its upper end and a cover therefor, a downwardly projecting shoulder on said container near the 10 open end thereof and a resilient member attached at its upper end to said cover and depending therefrom, said member having a laterally extending part near its lower end for engagement with the shoulder, and an obliquely extending 15 part projecting outwardly and downwardly from the inner edge of said laterally extending part, said last named part serving as a cam for bringing said fastener into engagement with said shoulder and as a finger piece for disengaging 20 said part from said shoulder.

17. In combination with a container open at its upper end and provided with means having a downwardly facing shoulder, a cover for the 25 open end of said container, a plurality of fingers for engagement beneath said shoulder, resilient means for attaching said fingers to said cover and urging said fingers toward the shoulder, and cams on said fingers for forcing said fingers 30 away from the container while the cover is being applied thereto.

18. In combination with a container open at its upper end and a cover therefor, a downwardly projecting shoulder on said container near the open end thereof, an elongated member attached at its upper end to said cover and depending therefrom, said member having a laterally extending part near its lower end for engagement with the shoulder and being bendable to procure engagement of said laterally extending part 40 with said shoulder, and a finger piece on said member disposed below said laterally extending part for disengaging said part from said shoulder.

19. In combination with a container open at its upper end and a cover therefor, a downwardly 45 projecting shoulder on said container near the open end thereof and an elongated bendable member attached at its upper end to said cover and depending therefrom, said member having a laterally extending part near its lower end for engagement with the shoulder, and an obliquely extending part projecting outwardly and downwardly from the inner edge of said laterally extending part, said last named part serving as a cam for bringing said fastener into engagement 50 with said shoulder and as a finger piece for disengaging said part from said shoulder.

WALTER E. HELLER.
